UNITED STATES PATENT OFFICE

ANDREW F. CAVANAUGH, OF DAYTON, OHIO

PROTECTING DEVICE FOR BANKS

Application filed October 3, 1930. Serial No. 486,207.

This invention relates to a protecting device for banks and other institutions which handle large sums of money in the course of a day's business.

5 One object of the invention is to provide means for so protecting the money on hand that only a relatively small portion thereof will be accessible at any one time during the day, thus in the event the bank is robbed the 10 amount stolen will be limited to that portion of the money which is accessible at the time of the robbery.

A further object of the invention is to provide such a device in which the money will be 15 divided among a plurality of compartments, according to the anticipated needs of the day's business, and those compartments will be rendered accessible one after the other at fixed intervals, by mechanism beyond the control of the officers of the bank.

20 A further object of the invention is to provide efficient time controlled mechanism for rendering the several compartments successively accessible at predetermined intervals.

25 Other objects of the invention will appear as the device is described in detail.

In the accompanying drawings Fig. 1 is a horizontal section taken through the casing of a device embodying my invention and 30 showing the mechanism in plan; Fig. 2 is a vertical section taken through such a casing, partly in elevation, and showing the mechanism in elevation; Fig. 3 is a transverse section taken on the line 3—3 of Fig. 1; Fig. 4 is a transverse section taken on the line 4—4 of Fig. 1; Fig. 5 is a transverse section taken on the line 5—5 of Fig. 1; Fig. 6 is a detail view of the locking member and its retaining device; Fig. 7 is a sectional detail view of the 40 device for rendering the emergency release operative; Fig. 8 is a circuit diagram of an electrically controlled device; Fig. 9 is a transverse section similar to Fig. 5, showing a modified form of controlling mechanism for the locking member; Fig. 10 is a side elevation of the mechanism shown in Fig. 9; Fig. 11 is a detail view of the retaining device of Fig. 9; and Fig. 12 is a detail view of a part of the emergency release of Figs. 9 and 10.

50 In these drawings I have illustrated one

embodiment of my invention and have shown in connection therewith both electrical and mechanical means for controlling the locking mechanism. It will be understood, however, that this embodiment has been chosen for the 55 purpose of illustration only and that the mechanism may take various forms and may be controlled in various ways without departing from the spirit of the invention.

In carrying out my invention I provide a 60 structure having a plurality of money compartments of such a character and so controlled that access can be had to but one compartment at any one time, in the course of a day's business, the several compartments being so controlled that they will be rendered 65 successively accessible at predetermined intervals. Thus by dividing the money among the several compartments in accordance with the anticipated needs of the day's business the 70 money in all the compartments save one will be securely locked against access at all times. The number of compartments, and consequently the duration of the intervals at which the compartments are rendered accessible, 75 may be varied according to the requirements of different users. Ordinarily a bank is open for business not to exceed six hours a day. The funds for the initial period are not placed in the protecting device but are placed 80 upon the counter in the usual manner. Therefore, it is not necessary to provide a compartment for the initial period of business. As a matter of convenience of illustration, I have 85 in the present instance shown five compartments, one for each hour after the first hour. Means are provided whereby access may be had to the several compartments at the beginning of the day's business to permit the 90 money to be divided among the same, but after the money has been divided the device is locked and the compartments will be accessible only at the predetermined intervals. The means which provides access to the several compartments at the beginning of the 95 day's business may be utilized to provide access to the compartments in case of an emergency during the day but the controlling means is of such a character that the compartments 100 will not be rendered accessible for a consid-

erable period after the emergency release has been operated, say fifteen minutes. Consequently in the event of a robbery it would be necessary for the robbers to wait in the banking room for this period of fifteen minutes before access could be had to the compartments, and it is seldom that the situation is such that they are willing to wait for that length of time.

10 In the particular embodiment of the invention here illustrated the apparatus comprises two relatively movable structures one of which contains the several compartments and the other of which is provided with an opening adapted to be brought into line successively with the several compartments by the relative movement of the two structures. These structures may take various forms and movement may be imparted to the movable structure in various ways but in the preferred form of the device I prefer that that structure which contains the compartments shall be movably mounted in a casing which is provided with an opening so arranged that the 15 movement of the compartment structure will bring those compartments successively into line with the opening. In the particular form here shown the compartment structure is circular in form, as shown at 10, and is mounted 20 on a shaft 11 for rotation in a casing 12 having an opening 13 in the wall thereof and adjacent to the periphery of the rotatable structure. The several compartments open 25 through the periphery of the rotatable structure and as this structure is rotated step by step these compartments will be brought successively into line with the opening 13, thus rendering them accessible. All the compartments except the one which is in line with the 30 opening 13 are completely closed by the casing and are therefore inaccessible. The compartments are formed by providing the rotatable structure with radial partitions 14 and suitable retaining devices, such as clamping 35 members 15 are provided to retain the money, which is usually paper money, within the respective compartments as the structure rotates. Any suitable means may be provided 40 for imparting rotatory movement to the receptacle or compartment structure 10. As here shown, that structure is rigidly secured to the shaft 11 and one end of the shaft extends through the end wall of the casing and is provided with a knob or hand wheel 16 by 45 means of which the shaft and the receptacle may be rotated. The rotatable structure as here illustrated is divided into six sections five of which constitute money compartments and the sixth of which has its outer end closed, as 50 shown at 17, and this closed section may be moved into line with the opening when access to all the money compartments is to be prevented, as, for example, during the first period 55 of the day's business.

60 The means for locking the rotatable struc-

tures in the different positions it assumes as the several compartments are successively moved into line with the opening in the casing, may take various forms. Preferably the rotatable structure is provided with a plurality of locking parts, one for each section of the structure, which parts are adapted to cooperate with a movable locking member mounted within the casing and adjacent to the rotatable structure. In the present instance a plate or disk 18 is rigidly secured to and forms part of the rotatable structure and has a series of apertures 19 adapted to receive a locking member, each apertured portion of the plate constituting a locking part for the rotatable structure. These locking parts or apertures are so arranged with relation to the several compartments that when any one of those compartments is in line with the opening 13 some one of the apertures will be in a position to receive the locking member, which is here shown as a bolt 20 slidably mounted in a bracket 21 and in standards 22 within the casing, the standards 22 also constituting supports for the shaft 25. Preferably the bolt 20 is yieldably 20 pressed toward the plate 18 so that it will enter one of the recesses 19 whenever a compartment is moved into line with the opening. As here shown, a collar 23 is secured to the bolt and a spring 24 is confined between that collar and out of the standards 22 and serves to press the bolt toward the locking plate 18. The locking member or plate 18 as here shown has peripheral teeth which are engaged by a detent 18a to hold the rotatable structure against reverse movement. Time controlled means are provided for controlling the movement of the bolt 20 to its inoperative position, that is, out of engagement with the locking member 18. In the present apparatus the time controlled mechanism merely releases the bolt for withdrawal and other means are provided for imparting movement to the bolt. For this purpose a retaining device 25 is slidably mounted in a bracket 26 and is provided with an opening 27 adapted to be moved into and out of line with the bolt 20. The position of the retaining device with relation to the bolt is such that when the opening 27 is out of line with the bolt the retaining device will positively prevent the withdrawal of the bolt from the locking member 18, but when the opening 27 is in line with the bolt the latter is free to move to its inoperative position. Manually operated means are provided for actuating the bolt after it has been released. As here shown, the bolt 20 is provided in its upper edge with a notch 28 and a latch or dog 29 is pivotally mounted on one arm of a bell crank 30 for movement into and out of the notch in the bolt. A push rod 31 is connected with the other arm of the bell crank and extends through the side wall of the cas-

ing and is provided with a head 32. The notch 28 in the bolt is so arranged that when the bolt is in its operative or locking position this notch will be in line with the dog 29 and if 5 the movement of the dog is unrestrained it will move by gravity into the notch and a thrust on the push rod 31 will cause the bell crank and the dog to move about the axis of the bell crank and thus withdraw the bolt. 10 After the bolt has been withdrawn the rotatable structure is advanced by means of the hand wheel 16, or otherwise, to move a succeeding compartment into line with an opening in the casing. To prevent the bolt being 15 held in its inoperative position while continued movement is imparted to the rotatable structure I have provided means controlled by the movement of the rotatable structure to move the latch or dog 29 out of engagement with the bolt and thus permit the same to 20 be again moved to its operative position by the spring 24. For this purpose I have mounted on the shaft 11 a cam 33 having one lobe for each compartment of the rotatable 25 structure and have rigidly connected with the dog or latch 29 an arm 34 having a nose 35 to ride over the surface of the cam. The cam is so arranged with relation to the rotatable structure that when one of the compartments is in its alined position the nose of the arm 34 will lie in the recess between two of the lobes of the cam, thus permitting the dog to enter the notch in the bolt. The first 30 movement of the rotatable structure will cause the cam to actuate the arm 34 and lift the dog 29 out of engagement with the bolt, thus automatically releasing the latter for operation by the spring. 35

In that form of the apparatus shown in 40 Figs. 1 to 8 the retaining device which holds the bolt normally in its locking position is actuated by electrically operated devices. In the preferred form one end of the retaining member is connected with a core 36 of a 45 solenoid 37 and the other end of the retaining member is connected with a core 38 of a solenoid 39. The circuits for both solenoids are normally open and each circuit is connected with a suitable source of current, such 50 as a battery 40. Interposed in one side of the circuit for the solenoid 37 is a time controlled circuit breaker and closer of such a character that it will close the circuit through the solenoid 37 at predetermined intervals. 55 will hold the circuit closed for a brief period of time and will then again open the same, thus energizing the solenoid for an interval sufficient to permit the core 36 to be retracted and the retaining device moved to 60 its inoperative position, that is, to a position in which the opening 27 therein will be in line with the bolt 20. In the present arrangement the circuit breaker and closer comprises an annular member 41 having thereon six contacts 42 spaced equal distances about 65 the circumference thereof. This annular member is rigidly mounted and is connected with the battery 40. The movable contact member is in the form of an arm 43 carried by a shaft 44 which is connected with and may form a part of a suitable motor adapted to be operated continuously at a uniform speed and which preferably comprises clock mechanism, as shown conventionally at 45. The speed of rotation of the shaft 44 is so 70 regulated that it will make one complete rotation in six hours, thus causing a contact member 43 to engage the respective contacts 42 at intervals of one hour. The arm 43 is of sufficient resiliency to permit the same to 75 yield and ride over the fixed contacts 42. The circuit for the solenoid 39 is controlled by the bolt 20 and, as here shown, I have interposed between the solenoid 39 and the battery a fixed contact member 46 and a movable contact member 47, the latter being in 80 the present instance carried by the bolt 20 and so arranged that it will operatively engage the fixed contact 46 upon the movement of the bolt to its operative position, thus 85 causing the solenoid 39 to be energized just prior to the completion of that movement of the bolt and the retaining device moved to 90 its operative position. As here shown, the fixed contact 46 is in the form of a resilient finger and the movable contact member 47 has on one side thereof a facing 49 of insulating material, so that the circuit will 95 not be closed when the bolt is moved to its inoperative position. 100

Therefore, it will be apparent that at intervals of one hour during a business day, or at such other intervals that may be determined upon, the rotatable structure will be released and may be advanced one step to bring a succeeding money compartment into line with the opening in the casing, whereby it will be rendered accessible. Upon the completion of this movement the rotatable structure is automatically locked and will not be again released until the end of the next interval of one hour. However, it is desirable that means should be provided for permitting the continued movement of the rotatable structure to enable the money to be placed in the several 110 compartments or to permit access to be had thereto in case of an emergency. I have therefore provided an emergency release and have so constructed the same that access cannot be had to the compartments until the end of a 115 definite period of time after the emergency release has been set in operation. In the present constructions the casing 12 has at one end thereof an opening 50 which is provided with a closure 51 normally held in its 120 closed position by a bolt 52 connected with and, if desired, forming the armature of a solenoid 53. The circuit for this solenoid is connected with the battery 40 and one side 125 of the circuit is connected with a fixed con- 130

tact member 54 which is here shown as adjustably mounted on a curved support 55 so that its position may be varied at will. The other side of the circuit is connected with a movable contact member 56 adapted to be moved into engagement with the fixed contact member 54 so as to close the circuit and energize the solenoid 53, but the movable contact member is time controlled and a definite interval must expire before it contacts with the member 54. As here shown, the movable contact member 56 is in the form of an arm rigidly secured to a clutch member 57 which is carried by the inner end of a shaft 58 slidably mounted in the side wall of the casing 12 and having on its outer end a handle 59 by means of which it may be manipulated. A spring 60 holds the shaft 58 normally in its retracted position. A second clutch member 61 is secured to a shaft 62 actuated by a motor, preferably the clock mechanism 45. When the shaft 58 is forced inwardly against the action of the spring 60 the two clutch members 57 and 61 will be operatively engaged and will be held in that position by means of a lug 63 on the shaft 58. This lug is normally mounted in a recess in the wall of the casing but is so arranged that when the shaft is moved inwardly to connect the clutches it will be moved out of the recess and will engage the inner surface of the wall. It will be apparent, therefore, that the movable contact member 56 is thus connected with the clock mechanism and will be brought into contact with the fixed contact member 54 after an interval of time determined by the distance between the two contact members. It will be noted that the clutch member 57 is rotatably mounted on the shaft 58 so that it may rotate with relation to that shaft and, when disconnected from the clutch member 61, the contact arm will move to its lowermost position by gravity, thus causing the movable contact member to be always spaced the same distance from the fixed contact member when the operative connection is established between the two clutches. When the solenoid 53 has been energized and the closure 51 unlocked this closure may be removed and free access is allowed to the interior of the casing. To facilitate the quick adjustment of the rotatable structure I have provided the circuit for the solenoid 37 with a manually operated switch 64 which, when closed, will bridge the time controlled circuit breaker and closer and maintain the solenoid energized, thus holding the retaining device in its inoperative position.

In Figs. 9 to 12 I have illustrated mechanical means for controlling the movement of the bolt 20. As there shown, the bolt retaining device is in the form of a plate 65 pivotally mounted at one end on a bracket 66 and having near the other end thereof an opening 67 movable into and out of line with

the bolt 20. Connected with the motor driven shaft 44 of the clock mechanism is an annular member 68 having thereon a plurality of trip devices 69 each of which is provided with an inclined surface. The retaining plate 65 has at its upper side a hook-shaped portion 70 which overhangs the annular members 68 and limits the downward movement of the retaining plate, the arrangement of this being such that when in engagement with the annular member 68 it will support the aperture 67 in the plate out of line with the bolt. The tripping devices 69 are spaced equal distances about the annular member and are adapted to engage beneath the hook shaped finger 70 and lift the retaining plate to bring the apertures into line with the bolt, this operation taking place at fixed intervals, in the present instance, once every hour. In order to hold the retaining device in its inoperative position for a period of time sufficient to give ample opportunity for the manipulation of the bolt to release the rotatable structure, the retaining plate has on its rear face a lug 90 which will engage a resilient latch 91 when the plate is elevated and hold it in its inoperative position until the bolt 20 is withdrawn. The latch is in the path of the bolt and will be engaged and actuated thereby to release the plate, thus permitting the latch to drop onto the bolt, and when the bolt is again moved to its locking position the retaining plate will move by gravity to its operative position. At the end of this period of time the tripping device moves out of engagement with the finger 70 and the retaining device moves by gravity to its operative position.

In the mechanically operated device the closure 51 for the opening in the end of the casing is locked in its closed position by a bolt 71 and this bolt is provided with a stud 72 arranged to be engaged by a trip member or cam surface 73 on a disk 74 which is secured to a clutch member 75 mounted on a shaft 76 similar to the clutch member and shaft 57 and 58 above described. A second clutch member 77 is connected with the motor and when the two clutch members are brought into operative engagement the disk 74 will be driven by the motor and after the lapse of a predetermined period the cam surface 73 will engage the stud 72 to move the bolt 71 to its inoperative position. The bolt is provided with a notch 78 and a latch 79 is pivotally supported above the bolt and is adapted to move by gravity into the notch when the bolt is moved to its retracted position and thus hold the bolt in that position. If desired, the bolt 71 may be extended to a point adjacent the rotatable actuating member 68 and provided with a lug 80 arranged in the path of a cam projection 81 on the rotatable member 68, this cam member being so arranged that it will engage the lug 80

and retract the bolt 71 at the end of a day's business.

While I have shown and described one embodiment of my invention I wish it to be understood that I do not desire to be limited to the details thereof as various modifications within the scope of the claims may occur to a person skilled in the art.

Having now fully described my invention 10 what I claim as new and desire to secure by Letters Patent, is:

1. A device of the character described comprising a structure having a plurality of compartments and a second structure arranged to close all but one of said compartments, one of said structures being movable with relation to the other structure to successively open said compartments, and time controlled locking mechanism to retain said movable structure in each successive position for a predetermined interval.

2. A device of the character described comprising a structure having a plurality of compartments and a second structure arranged to close all but one of said compartments, one of said structures being movable with relation to the other structure to successively open said compartments, and means including a continuously operating motor to advance said movable structure step by step at intervals determined by said motor.

3. A device of the character described, comprising a structure having a plurality of compartments, and a second structure arranged to close all but one of said compartments, one of said structures being movable with relation to the other structure to successively open said compartments, mechanism to lock said movable structure in each position to which it is moved to open one of said compartments, and time controlled means to control the operation of said locking mechanism to release said movable structure.

4. A device of the character described, comprising a structure having a plurality of compartments, and a second structure to close all but one of said compartments, one of said structures being movable with relation to the other structure to successively open said compartments, mechanism to lock said movable structure in each position to which it is moved to open one of said compartments, time controlled means to control the operation of said locking mechanism to release said movable structure, and means for advancing said movable structure after it has been released.

5. A device of the character described comprising a structure having a plurality of compartments and a second structure arranged to close all but one of said compartments, one of said structures being movable with relation to the other structure to successively open said compartments, said mov-

able structure having a locking part for each operative position thereof, a locking member, means for automatically moving said locking member into locking engagement with said locking parts as they are moved into line therewith, means to normally retain said locking member in engagement with one of said locking parts, and time controlled means for releasing said locking member at fixed intervals of time.

6. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, means to normally prevent the withdrawal of said locking member, and time controlled means for releasing said locking member for withdrawal at fixed intervals of time.

7. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, means to normally prevent the withdrawal of said locking member, time controlled means for releasing said locking member for withdrawal at fixed intervals of time, and means controlled by the movement of said movable structure to disconnect said withdrawing means from said locking member.

8. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, a retaining device movable into and out of a position to hold said locking member against withdrawal, time

controlled means to move said retaining device to a position to release said locking member, and means for moving said retaining device to its holding position when said locking member is restored to its operative position.

9. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, a retaining device movable into and out of a position to hold said locking member against withdrawal, time controlled means to move said retaining device to a position to release said locking member, and means controlled by said locking member for moving said retaining device to its holding position when said locking member is restored to its operative position.

10. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, a retaining device movable into and out of a position to hold said locking member against withdrawal, a motor adapted to operate continuously at a uniform speed, and means controlled by said motor to move said retaining device to an inoperative position at fixed intervals.

11. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, a retaining device movable into and out of a position to hold said locking member against withdrawal, a motor adapted to operate continuously at a uniform speed, and means controlled by said motor to move

said retaining device to an inoperative position at fixed intervals, and to then release the same for movement into its operative position.

12. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, a retaining device movable into and out of a position to hold said locking member against withdrawal, a motor adapted to operate continuously at a uniform speed, means controlled by said motor to move said retaining device to an inoperative position at fixed intervals, and to then release the same for movement into its operative position, and means controlled by the movement of said locking member to its locking position to move said retaining device to its operative position.

13. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, a retaining device movable into and out of a position to hold said locking member against withdrawal, electrically operated means to move said retaining device to its inoperative position and comprising a normally open circuit, and time controlled means to close said circuit at intervals.

14. A device of the character described comprising a structure having a plurality of compartments and a second structure arranged to close all but one of said compartments, one of said structures being movable with relation to the other structure to successively open said compartments, said movable structure having a locking part for each operative position thereof, a locking member, yieldable means to move said locking member into locking engagement with said locking parts successively as they are moved into line therewith, means for withdrawing said locking member, a retaining device movable into and out of a position to hold said locking member against withdrawal,

electrically operated means to move said retaining device to its inoperative position and comprising a normally open circuit, time controlled means to close said circuit at intervals and to open said circuit after said retaining device has been actuated, electrically operated means to move said retaining device to its operative position and comprising a normally open circuit, and means controlled by the movement of said locking member to its locking position to close the last mentioned circuit.

15. In a device of the character described, a casing having an opening in a wall thereof, a structure rotatably mounted in said casing and having a plurality of compartments arranged to move successively into line with said opening as said structure is rotated, locking mechanism to normally lock said structure against rotation when any one of said compartments is in line with said opening, and time controlled means to control the operation of said locking mechanism to release said structure.

20. 16. In a device of the character described, a casing having an opening in a wall thereof, a structure rotatably mounted in said casing and having a plurality of compartments arranged to move successively into line with said opening as said structure is rotated, a movable locking member, means to move said locking member into locking relation to said rotatable structure when one of said compartments is in line with said opening, time controlled means to normally hold said locking member in locking position and to release the same at intervals, and means to move said locking member out of its locking position when it has been released.

25. 17. In a device of the character described, a casing having an opening in a wall thereof, a structure rotatably mounted in said casing and having a plurality of compartments arranged to move successively into line with said opening as said structure is rotated, a movable locking member, means to move said locking member into locking relation to said rotatable structure when one of said compartments is in line with said opening, a retaining device to normally prevent the movement of said locking member from its locking position, time controlled means to actuate said retaining device at intervals to release said locking member, means for moving said locking member out of its locking position when it has been released, and means controlled by the movement of said locking member to its locking position to move said retaining device into operative relation to said locking member.

30. 18. In a device of the character described, a casing having an opening in a wall thereof, a structure rotatably mounted in said casing and having a plurality of compartments arranged to move successively into line with

said opening as said structure is rotated, locking mechanism to normally lock said structure against rotation when any one of said compartments is in line with said opening, time controlled means to control the operation of said locking mechanism to release said structure, said casing having a second opening to afford access to the interior thereof, a closure for said second opening, a lock to secure said closure in its closed position, normally inoperative time controlled means for actuating said lock to release said closure, and manually operated means to render the last mentioned time controlled means operative.

35. 19. In a device of the character described, a casing having an opening in a wall thereof, a structure rotatably mounted in said casing and having a plurality of compartments arranged to move successively into line with said opening as said structure is rotated, locking mechanism to normally lock said structure against rotation when any one of said compartments is in line with said opening, time controlled means to control the operation of said locking mechanism to release said structure, said casing having a second opening to afford access to the interior thereof, a closure for said second opening, a lock to secure said closure in its closed position, an actuating device for said lock mounted in said casing and comprising two parts spaced one from the other, normally inoperative means for moving one of said parts into operative engagement with the other part, and manually controlled means for rendering said normally inoperative means operative.

In testimony whereof, I affix my signature hereto.
